PLAYING GAME

Benjamin A. Oehler, St. Louis, Mo.

Application November 18, 1936, Serial No. 111,451

1 Claim. (Cl. 273—147)

This invention relates to the improvements in a playing game in the form of a hand-spinning top having designating positions thereon for indicating either advancement or recession of each player in a game representing baseball or the like, wherein advanced or retrograde positions of players may be indicated on the device or top, when spinning thereof has ceased.

The main object of the invention is to provide a hand spinning device such as a top with indications adjacent its perimeter and having a pivotally mounted pointing element thereon which is capable of independent spinning movement.

Another object of the invention is to provide a hand-spinning device for playing game purposes, in the form of a disc which is fixedly secured to a centrally disposed peg by which the device may be spun and with a pointer loosely turnable on the peg in the plane of the disc for pointing cooperation with identifying characters on the disc.

Other objects and advantages will appear as this description progresses and by reference to the drawing, in which:—

Figure 1 is a top plan view of a top or spinning device having the invention applied thereto.

Figure 2 is a transverse vertical section taken approximately on the line 2—2 of Fig. 1.

Figure 3 is a top plan view showing a modification of the invention.

Referring by numerals to the accompanying drawing, 3 designates a disc which may be made from relatively stiff card board or metal or any material presenting a stiffness, said disc having a centrally disposed sleeve 4 securely fixed thereto, and said sleeve having prongs 5 on its upper end for indenting engagement with the turning peg 6 for securely fixing the disc 3 to the peg.

Before mounting and securing the disc 3 to the peg 6, a pointer 7 having an intermediately disposed opening, is mounted on the extending end of the sleeve 4, the opening of the pointer being of a size to permit the pointer being loosely mounted on the sleeve, and for spacing the pointer above the disc 3, a shoulder 8 is provided on the sleeve, and on which the pointer rests or seats.

The disc 3, its centrally secured sleeve 4 and the pointer 7, are mounted together on the reduced end 9 of the peg 6 and the prongs 5 of the sleeve are then pressed into the shouldered end 10 of the peg. This manner of securing the device together will rigidly fix the disc 3 to the peg 6 and at the same time provide the pointer 7 free for rotary movement on the sleeve 4.

The disc 3 on its top surface adjacent its perimeter is provided with a plurality of indications denoting terms used in a baseball game, as designated at 11, and said disc on its perimeter is also provided with a plurality of projections 12, said projections being for the purpose of engagement by a player to stop rotation of the device after spinning the same, or the device may be stopped from spinning by engaging the button 13 which is secured on the upper end of 10 the peg 6.

In playing a game of baseball with this improved device, a player will engage the button 13 and upon twirling the same for spinning the disc 3, the pointer 7 by reason of it being loosely mounted on the sleeve 4 of the peg, will of course be displaced; firstly, on the impulse of twirling or rotating the disc before the pointer is picked up by the twirling momentum of the disc or peg, and secondly, by the sudden stopping of the disc 20 which will result in the pointer subsequently stopping at random on one of the several indications 11, as denoting an action or position in the baseball game which the player must assume in advancing or receding a position, as required in 25 the game.

The reason for stopping the revolving of the disc 3 by touching or engaging the projections 12 thereof, or by engaging the button 13 shortly after twirling it, is for the purpose of eliminating the 30 time which would otherwise be required for the twirling momentum to cease, and so that a game among players may progress with some activity and speed.

Players in succession may take turns in twirling and stopping the device for freely shifting 35 the pointer 7 to an at random directing position, and if desired, a playing chart with movable objects may be used in conjunction with the device.

The modified showing in Fig. 3 is that of a 40 cover disc 15 which is loosely mounted on the turning peg 18 over the disc 14 and said disc 15 having a recess 16 at its perimeter through which the terms or characters 11 on the fixed disc 14 can be seen, said disc 15 and its recess 16 answering the purposes of the pointer 7 shown in 45 Figs. 1 and 2, when the device is spun by twirling the button 17 of the plug 18.

Obviously constructional modifications of the device are possible without departing from the 50 spirit of the present invention and therefore it is to be understood that it is not necessary to limit the invention by the terms used in the foregoing description, excepting such as the state of the art may require.

What I claim is:—

A spinning device comprising a disc having a shouldered supporting peg, a sleeve to which said disc is fixedly secured and said sleeve at one end having a prong penetrating the shoulder for securing it to the peg, radially disposed indicating

characters on the top surface of said disc, and indicating means freely mounted on said sleeve between the shoulder of said peg and said disc for cooperation with said characters.

BENJAMIN A. OEHLER.
